UNITED STATES PATENT OFFICE

SEIKICHI SATO, OF SENDAI, JAPAN

SELF RECORDING DILATOMETER

Application filed February 25, 1932. Serial No. 595,170.

My invention relates to an automatic recording device of the thermal dilatation of a test specimen.

The object of my invention is to provide an automatic device for mechanically recording a temperature versus thermal expansion curve or the relation between temperature and time directly without troubles and a long time even in the case of quenching a specimen wherein quick cooling is necessary so as not to be observed by an ordinary dilatometer so that the quenching effects in different cooling media and at different temperatures may be easily compared and the nature of quenching medium and quenching methods for various materials can be simply determined, and it has useful applications in practical engineering.

Referring to the accompanying drawings, Fig. 1 is a plan view of the present device; Fig. 2 is a side view of the supporting rod together with its securing parts; Fig. 3 is a sectional view taken on the line A—A of Fig. 1; Fig. 4 is a partial plan view of a modified form of this invention; Fig. 5 is a side view of a constant motion transmitting device, a portion being taken in section and Fig. 6 is its plan view.

In order to investigate a transformation of iron, steel and other metals or metallic alloys during the heat treatment, or more generally the change of physical and metallurgical properties of such a material due to the change of temperature, it has heretofore been considered that the most effective method is to observe the change in length or volume of the material to be tested at different temperatures and there have been generally taken such steps by using a thermal dilatometer, yet in case of a very rapid change of temperature such as in quenching process no observation can be taken by an ordinary device.

In such cases, the temperature and thermal expansion curve may be taken on photographic plates or films by means of an optical device. But such a process requires much time and labour as the operation is very troublesome and also as it requires other auxiliary devices to be combined therewith and it is found not only difficult to a common engineer who has usually no suffi-

cient installations of investigation, but also the curve obtained by a photographing device is generally inaccurate and not clear. Moreover when the test piece is to be quenched in water or oil, or other various coolants and also when the quenching is effected in the same medium of different temperatures, the above mentioned ordinary process can hardly be adopted for practical and important fields.

My invention is to avoid such disadvantages. Now I will explain my invention referring to the drawings which illustrates an automatic recording device of thermal expansion embodying my invention. In Fig. 1, 1 represents a base plate, 2 represents a bracket secured to the base 1, and from the bracket 2 is projected a hollow supporting rod 3 made of high refractory material having a very small coefficient of thermal expansion such as fused quartz, 4 represents a supporting guide rod made of high refractory metal such as nickel-chromium alloy having a guide member 5 fixed thereto. 6 and 7 are thin pipes made of the same material as that of the supporting rod 3, serving as the motion transmitting rod and are suitably supported by the bracket 2 and the guide piece 4 in parallel relation.

Two levers 8 and 9 are pivoted on a common fulcrum 12 secured to the base 1, of which the lever 8 is arranged in parallel to the transmission rods 6 and 7, while the other lever 9 is arranged at right angle to these rods. Free ends of these levers 8 and 9 are connected together by means of connecting links 10 and 11 to form a regular quadrilateral or a parallelogram. To a projecting arm 8' of the lever 8 is attached an adjusting screw 13 and to the other lever 9 is attached the similar adjusting screw 14. These screws are provided for adjustably supporting each end of the transmission rods 6 and 7 respectively. 17, 18, 19 and 20 are joint levers forming a pantograph mechanism, of which the lever 17 is connected to the joint of links 10 and 11, and the lever 19 is pivoted at 23 to the base. 21 and 22 represent balance weights. The lever 20 is extended to a required length and has a pen tip

24 at its free end. 25 represents a recording board secured to the base 1 by means of a clamping screw 29. The pivots 12 and 23 are preferably provided with ball bearings 5 for reducing the friction. Light tension springs 15, 16 and 26 secure a good contact between fixed and moving parts. The base 1 is provided with a handle 27 so as to facilitate the total device to be grasped by a hand 10 and 28 represents a finger grip.

In the above device, a test piece T is to be held in position between the T-shaped end of the supporting rod 3 and the front end of the transmission rod 7 and a standard rod S may 15 be put between the T-shaped end of the supporting rod 5 and the front end of the other transmission rod 6. The standard rod S may be made of nickel-chromium alloy or iron-nickel-chromium alloy which has uniform 20 coefficient of thermal expansion and presents no abnormal change of the thermal expansion and has the specific heat and density similar to those of the test piece T.

Now I will describe the manner of taking 25 the temperature versus thermal expansion curve of a certain test specimen by means of the above described device embodying my invention. It is preferable to adjust counter weights 21 and 22 and also springs 15, 16 and 30 26 as well as adjusting screws 13 and 14 to make the levers 8, 9, 10 and 11 to form a regular quadrilateral and to bring the pen 24 to a predetermined position on the recording board 25. After such adjustment, all 35 parts of the present device are settled and the position of the pen is not changed even if the device is tilted or overturned. The center of the joint E between levers 10 and 11 should preferably lie on a straight line connecting 40 the pivot 23 and the pen tip 24, then the curve or figure drawn on the recording board 25 by the pen 24 is similar to, but at a desired 45 enlargement determined by the ratio of the arm length, the movement traced by the point E. The levers 8, 9 and the pantograph levers are preferably made of duralumin, as for instance, in order to possibly reduce the weight.

When the device is prepared as above described 50 with the test piece T and the standard rod S held in position on the T-shaped supporting rod 3, they are heated in a suitable heating furnace or other heating means. Then the thermal dilatation i.e. (expansion or 55 contraction) caused by the test piece T and standard rod S are transmitted through the transmission rods 6 and 7, and the movements of these rods are magnified by the levers 8 and 9, and composed by links 10, 60 11 to the point E at right angles to each other and this combined movement of the point E is still enlarged by the pantograph mechanism and drawn on the recording board 25 by the pen 24. The change in length of the standard 65 rod S serves to indicate the temperature

of the test specimen at any moment, and therefore the relation between the temperature and the thermal expansion of the test rod T can be drawn on the recording board based on rectangular coordinates. The scale 70 of temperature recorded by the thermal expansion of the rod S should be determined by a thermo-couple heated to the same condition as that of the rods S and T. It naturally depends upon the coefficient of thermal 75 expansion of the material constituting the standard rod S, but it can be easily predetermined.

In heating the rod S and the test piece T as they are held in position on the present device they may be placed into a furnace having a uniform distribution of temperature, then the pen tip 24 will draw a heating curve so that the operator may inspect directly 80 the manner of transformation occurring in the test specimen. If it is desired to quench the test specimen from a desired temperature the present device may be pulled out of the furnace by the operator who holds the device by the handle 27 and the grip 28, or the present device may be suspended from a suitable support and the furnace may be shifted along fixed rails and the test specimen T and the rod S can be transferred on a quenching tub by holding the handle 27 and grip 28, and the heated portions are plunged into the quenching fluid in the tub quickly. Then the manner and temperature of the transformation occurring during the course of quenching can be directly observed by the quenching curve drawn by the pen tip 24 so that 85 the quenching effect may be judged at once and also the effect of cooling fluid on quenching can be judged at the same time.

In a modified form of this invention partially shown in Fig. 2 the lever 8 is replaced by a constant speed device 30 such as a watch mechanism which is secured to the base 1 at 40. The device 30 is more clearly shown in Figs. 3 and 4, wherein 30 represents a suitable 100 watch mechanism or a synchronous motor (its inner gears not shown). The revolving shaft 31 has fixed thereto a pinion 32 by means of a set screw 33 and a toothed wheel 34 gearing with the pinion 32 is secured to the end of a screw shaft 35, with which engages a plunger 37 guided in the sleeve 36 and to the plunger 37 is connected the rod 10 (Fig. 2) which forms one side of the quadrilateral, and the levers constituting the pantograph are arranged similarly to those shown in Fig. 1. In this case, the point G is moved on a straight line normal to the center line of the watch mechanism 30 at a constant speed and accordingly the motion of the point G will describe a definite time. 38 (Figs. 3 and 4) represents a starting push button and 39 represents a lug for securing the constant speed mechanism to the base. In some cases a similar constant motion mechanism may be 115 120 125 130

secured to the end of the lever 8 in Fig. 1, or the movement of the lever 8 may be arrested by putting a piece of silica tube in place of the rod S and an uniformly revolving recording drum may be used instead of the recording board 25 to attain the object of this invention equally.

With the modified arrangement shown in Fig. 2, the time and temperature curve can be drawn by the present device. If in this case the watch mechanism 30 is not started just before the quenching is to be effected and the test piece only is heated then the pen 24 is shifted almost parallel to the axis of the test piece so that it describes the expansion only. When a suitable temperature is arrived at the watch mechanism is started and the test piece is quenched into a cooling liquid, then the time and thermal expansion or contraction curve can be obtained so that the period at which the transformation occurs during the course of quenching and also its progress can be observed. If a standard rod S is put instead of the test piece T in the apparatus shown in Fig. 2 the time and temperature curve can be obtained so that it can be utilized for the comparison of cooling characteristics of different quenching liquids or for the observation of their cooling speeds. It will be easily understood that the device shown in Fig. 1 can be easily changed into the device partially shown in Fig. 2 by simply taking off the lever 8 of Fig. 1 and by replacing it with the watch mechanism 30 shown in Figs. 2, 3 and 4, or more simply by arresting the movement of one of the levers 8 or 9 by replacing one of the rods S or T with a piece of silica tube, thus limiting the motion of the pen in one direction only along the axis of an uniformly revolving recording drum in place of the board 25.

In accordance with my invention the temperature and thermal expansion curve as well as the relation between the time and temperature or thermal expansion of a test piece can be directly and automatically drawn on a recording board or on the paper attached thereto by mechanical means so that it has not only the advantages of facilitating to inspect the manner of transformation occurring in the test piece but also of determining the nature of any quenching medium. The present device is of light construction and manufactured at a lower cost and adapted for easy handling.

In the foregoing description, the term "thermal expansion" means "thermal expansion or contraction."

What I claim as new and desire to secure by Letters Patent of the United States, is:

1. A portable self-recording dilatometer adapted for recording the relation between the temperature and the thermal change as well as their time function by entirely mechanical means on a plane recording board

in a rectangular coordinate system, comprising a portable base, a T-shaped supporting rod of a material having a very small coefficient of thermal expansion rigidly secured to said base and projecting therefrom, a pair of thin pipes of material having a very small coefficient of thermal expansion arranged in parallel on the opposite sides of said supporting rod, brackets secured to the base for slidably receiving the pipes, a pair of swing levers pivoted to said base on the same axis, one of said levers being parallel to said transmission rods while the other is arranged normally to said transmission rods in their initial positions and both levers being in engagement with said transmission rods respectively, links connected to the free ends of each of said levers to form a quadrilateral therewith, a pantograph mechanism associated with a point on said quadrilateral links, one member of said pantograph being pivoted to said base and the last member thereof being extended to provide a pen tip, a plane recording board supported by the base to cooperate with said pen tip, springs attached to said swing levers and pantograph mechanism so as to maintain their parts at normal condition to enlarge the resultant movement of said quadrilateral, a test piece and a standard piece being adapted to be held in position between free ends of said supporting rod and transmission rod respectively so that the thermal dilatation of said test piece and standard piece may be transmitted to the cooperating swing lever respectively and the resultant movement of a point on said parallelogram may be multiplied by said pantograph mechanism and recorded mechanically.

2. A portable self-recording dilatometer adapted for recording the relation between the temperature and the thermal change as well as their time function by entirely mechanical means on a plane recording board in a rectangular coordinate system, as claimed in claim 1, wherein one of said swing levers is replaced by a constant speed mechanism secured to said base adapted to move its plunger along a straight line in the direction normal to the central axis of said constant speed mechanism so as to form a quadrilateral which is connected to said pantograph mechanism.

In testimony whereof, I have signed my name this 27th day of January 1932.

SEIKICHI SATO.
